US00D496196S1

(12) **United States Design Patent**
Fritzsche et al.

(10) Patent No.: **US D496,196 S**
(45) Date of Patent: **** Sep. 21, 2004**

(54) **DISPLAY FRAME POST**

(75) Inventors: **Mark Fritzsche**, Eagan, MN (US); **Dan Berg**, Minneapolis, MN (US); **Jason Johnson**, Minneapolis, MN (US)

(73) Assignee: **Skyline Displays, Inc.**, Eagan, MN (US)

(**) Term: **14 Years**

(21) Appl. No.: **29/190,365**

(22) Filed: **Sep. 18, 2003**

Related U.S. Application Data

(63) Continuation-in-part of application No. 09/953,111, filed on Sep. 13, 2001.

(51) **LOC (7) Cl.** **06-06**

(52) **U.S. Cl.** **D6/495**

(57) **CLAIM**

We claim the ornamental design for display frame post, as shown and described.

DESCRIPTION

The sole FIGURE is a perspective view. Due to the symmetry of the design, this perspective view is the same from both ends and all sides of the claimed invention. The perspective view of FIG. 1 fully and completely discloses the appearance of the display frame post design.
